EXHAUST FAN

Frederick J. Hoffman, Seattle, Wash., assignor to
Hydraulic Supply Manufacturing Company,
Seattle, Wash.

Application October 18, 1950, Serial No. 190,775

4 Claims. (Cl. 98—43)

1

My invention relates to fan assemblies; and, more particularly, to an exhaust fan. My fan is designed to prevent fouling of the fan blades, motor and the passageway in which the fan is positioned, and to provide convenient access to the passageways through which air from an enclosure is exhausted, for cleaning and maintenance purposes. A circular main housing is positioned in an opening in an enclosing member of a room or the like. A circular fan housing is positioned within the main housing in spaced relationship and contains a fan. The fan is disposed to direct air from outside toward the inside of the enclosure. A dome-shaped baffle is positioned in front of the exhaust of the fan with its edges extending between said housings in spaced relationship. The width of the space between the edge portion of the baffle and the fan housing is less than the width of the space between the adjacent unobstructed space between housings. Air impinging on the baffle passes through a restricted passageway between the baffle and fan housing and expands into the larger passageway between the fan and the main housing. This acts in the manner of a Venturi tube and draws air from the enclosure through the passageway between the baffle and the main housing and exhausts the same outside of the enclosure. The baffle is removable providing convenient access to all passageways through which air from the room passes, for cleaning and the like.

A problem common to exhaust fans is to prevent fouling fan blades, motor and passageway in which the fan is positioned. A related problem is to provide convenient access to the passageways through which room air passes, for cleaning and the like. Depending upon the type of activity within a room, the type of heating used, etc., the air in the room has various amounts of impurities therein which deposit on exhaust passageways. If the air passes through the fan blades, motor and fan passageway, these portions are fouled and require cleaning to maintain the fan in proper operating condition. Often there is oil on these portions and this aggravates the fouling. Unless the fan assembly is frequently cleaned, an unsightly appearance is presented; and the fan assembly itself, when open to view as in the ordinary exhaust fan, is not attractive.

It is an object of my invention to prevent fouling of the fan assembly in an exhaust fan; to provide convenient access to the room air exhaust passageways in an exhaust fan; to improve

2

the appearance of an exhaust fan; to exhaust air from a room by a fan without passing the air through the fan blades, motor and fan housing; to provide an economically manufacturable exhaust fan which is easily installed in a room; to minimize maintenance of an exhaust fan; to provide ready access to the moving parts in an exhaust fan; and to apply the principles of a Venturi tube to exhaust fans to reduce cleaning maintenance of moving and oily parts.

My invention will best be understood from the following description, when read with reference to the drawings, in which:

Figure 1 is a side view, partly in section, of a specific embodiment of my exhaust fan, with a portion of the wall in which the fan is positioned;

Figure 2 is a view taken on line 2—2 of Figure 1, partly in section;

Figure 3 is a sectional view taken on line 3—3 of Figure 2; and

Figure 4 is a diagrammatic view showing louver operating means for sealing the fan opening when the same is not in use.

Main housing 10 is positioned in an opening in the enclosing member 12 of a room or the like. In the form shown, housing 10 is made of two portions of sheet metal, one portion 16 being on the room air inlet side and the other portion 18 being on the air outlet side, secured together by screws 20. Portion 16 carries flange 22 which abuts the inner surface of enclosing member 12. Main housing 10 is circular in transverse cross-section.

Fan housing 30 is positioned within main housing 10 and is also of circular transverse cross-section. Housing 30 is secured in place by bolts 32 and nuts 34 and is spaced from main housing by spacers 36.

Fan motor 40 is set within fan housing 30 on strap 42. Fan blades 44 are disposed to direct air from outside enclosing member 10 toward the inside of the room. Louver means 46, shown in dotted lines in Figure 1, may be used to protect and conceal the fan.

In Figure 4 a suitable louver operating means is shown, diagrammatically. As motor 40 is energized by the usual switch a solenoid 47 is also energized and louver blades 46 are moved to their open position. It is to be noted that the upper louver blades 46-a and the lower louver blades 46-b are operated through modified linkage having specially positioned attachment points to operate the upper and lower louvers after the showing of Figure 1. This arrangement is de-

sirable as it assures that the louvers will not interfere with the optimum path taken by the air being discharged out of the annular opening 82.

Dome-shaped baffle 50 is positioned in the path of air from the fan to reverse the direction of flow of the air. Baffle 50 is removably connected to fan housing 10 by spacers 52, having spring-pressed ball detents 54 setting in recesses in the edges of baffle 50. An inwardly projecting central portion 56 of baffle 50 is directed toward the center of fan blades 44. Rod 58, across inwardly projecting portion 56, provides means for pulling baffle 50 from engagement with detents 54.

Portion 18 of main housing 10 is flared outwardly at 60 on the outer side of enclosing member 12. Fan housing 30 is similarly flared at 62. Except for flare 62, the outer surface of fan housing 30 is convexly curved longitudinally. The inner surface of fan housing 30 is concavely curved longitudinally. Flare 62 and the outside portion of the inner surface of fan housing 30 are formed by bending fan housing 30 and doubling it back on itself, as at 64. The doubled portion is secured as by screws 66. The purpose of the outward flare of main housing 10 at 60, the outward flare of fan housing 30 at 62 and the doubled portion of fan housing 30, is to prevent intermingling of air passing out at 68 between housing 10 and housing 30 with air entering fan housing 30 at 70.

As the fan directs air against baffle 50, the air is curved to pass through a restricted passageway at 80 between fan housing 30 and baffle 50. Then the air passes into an enlarged passageway at 82 in the unobstructed areas between fan housing 30 and main housing 10. This expansion from a restricted to a larger passageway acts in the manner of a Venturi tube and air is drawn from the room through the passageway at 84 between baffle 50 and main housing 10 and into the enlarged passageway at 82 and out through the flared opening at 68.

As will be observed, air from the room does not pass inside of fan housing 30, but passes between main housing 10 and fan housing 30. This passageway is not oily and is formed to collect a minimum of deposits from the room air. Removal of baffle 50 provides ready access to the room air passageway for cleaning. Removal of the baffle also affords ready access to the fan for maintenance of the same, and any deposits from the outer air collecting inside fan housing 30 or on baffle 50 may be removed. When baffle 50 is in place, the exhaust fan assembly presents a pleasing appearance from inside the room as only baffle 50 and portion 16 of main housing 10 are visible.

Although I have shown a specific embodiment of my exhaust fan, I wish to be understood as not limiting myself to the depicted device but wish to claim all devices fairly within the scope of my invention.

I claim:

1. An exhaust fan for exhausting air through an enclosing member of a room or the like, comprising: a main housing to be positioned in said enclosing member having an air ingress opening at one side and an air egress opening at the other side of said enclosing member, said main housing being circular in transverse cross-section and being flared outwardly at said air egress opening; an open-ended fan housing positioned within said main housing, said fan housing being circular in transverse cross-section and being spaced from said main housing providing an annular exhaust air passageway between said housing, the

5

inner surface of said fan housing being concavely curved longitudinally and the outer surface of said fan housing being convexly curved longitudinally except that it is flared outwardly opposite the outward flare of said main housing; a dome-shaped baffle removably positioned at the air ingress side of said main housing with its concave face inward, the edge of said baffle being positioned between said main housing and said fan housing in spaced relationship, the width of the space between said edge of said baffle and said fan housing being less than the width of the adjacent portion of said annular exhaust air passageway; a fan positioned in said fan housing and disposed to direct air against said baffle and to draw air from the opposite end of said fan housing, air passing from said baffle into said annular exhaust air passageway toward said air egress opening drawing air through said air ingress opening of said main housing; and said baffle having a central inwardly projecting portion directed toward the center of said fan.

20

2. An exhaust fan for exhausting air through an enclosing member of a room or the like, comprising: a main housing to be positioned in said enclosing member having an air ingress opening at one side and an air egress opening at the other side of said enclosing member, said main housing being annular in transverse cross-section; an open-ended fan housing positioned within said main housing, said fan housing being annular in transverse cross-section and being spaced from said main housing providing an annular exhaust air passageway between said housings; a baffle positioned at the air ingress side of said main housing with the edges thereof being positioned between said main housing and said fan housing in spaced relationship, the width of the space between said edge of said baffle and said fan housing being less than the width of the adjacent portion of said annular exhaust air passageway, the central portion of said baffle being protuberant outward; a fan positioned in said fan housing and disposed to direct air against said baffle and to draw air from the opposite end of said fan housing, air passing from said baffle into said annular exhaust air passageway toward said air egress opening drawing air through said air ingress opening of said main housing.

30

3. An exhaust fan for exhausting air through an enclosing member of a room or the like, comprising: a main housing to be positioned in said enclosing member having an air ingress opening at one side and an air egress opening at the other side of said enclosing member; an open ended fan housing positioned within said main housing and spaced therefrom providing an exhaust air passageway between said housings; a fan positioned in said fan housing; a baffle positioned at the air ingress side of said main housing, said fan being disposed to direct air against said baffle and to draw air from the opposite end of said fan housing, said baffle being formed to direct air striking said baffle into said exhaust air passageway in a direction toward said air egress opening of said enclosing member, and said baffle being disposed so that air passing through said fan and against said baffle passes from a restricted space between said baffle and said fan housing into the larger space of said exhaust air passageway thereby drawing air through said air ingress opening of said main housing.

40

4. An exhaust fan for exhausting air through an enclosing member of an enclosure, comprising:

ing: a fan assembly to be positioned in an opening in said enclosing member, having a fan disposed to draw outside air from without said enclosing member and direct said outside air toward the inside of said enclosing member; having a baffle positioned on the exhaust side of said fan and formed to reverse the flow of said outside air to direct it toward the outside of said enclosing member; having means forming a restricted passageway for said outside air after its flow has been reversed by said baffle; having means forming a larger passageway, connecting with said restricted passageway, leading to the outside of said enclosing member, whereby air passing through said restricted passageway has room to expand in said larger passageway; and having means forming an air passageway leading from the inside of said enclosing

member and connecting with said large passageway near its junction with said restricted passageway, whereby air passing from said restricted passageway will draw air from inside said enclosing member.
